Specification for Design.

Patented Jan. 16, 1917.

Application filed November 4, 1916. Serial No. 129,617. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Glass Plate or Similar Article, of which the following is a specification, reference being had to the accompanying drawings, forming a part thereof and which illustrate my new design, wherein—

Figure 1 is a view in top plan of the

plate; Fig. 2 is a view partly in side elevation and partly in sectional elevation, the portion in section being taken on line 2—2 of Fig. 1, and Fig. 3 is a bottom plan of the plate.

I claim:

The ornamental design for a glass plate or similar article, substantially as shown.

REUBEN HALEY.
